UNITED STATES PATENT OFFICE

STEPHEN SLESINGER, OF NEW YORK, N. Y., ASSIGNOR TO STEPHEN SLESINGER, INC.,
OF NEW YORK, N. Y., A CORPORATION OF NEW YORK

DESIGN FOR A CUP OR SIMILAR ARTICLE

Application filed February 25, 1932. Serial No. 42,996. Term of patent 3½ years.

To all whom it may concern:

Be it known that I, STEPHEN SLESINGER, citizen of the United States, residing at New York city, county of New York, State of New York, have invented a new, original, and ornamental Design for a Cup or Similar Article, fully described and represented in the following specification and the accompanying drawing forming a part of the same in which

Figure 1 is a side elevation of a cup or similar article showing ornamentation on one side thereof;

I claim:

The ornamental design for a cup or similar article as shown and described.

In testimony whereof I have hereunto set my hand.

STEPHEN SLESINGER.
